CLAIM

The ornamental design for a toy car, as shown and described.

DESCRIPTION

FIG. 1 is a front perspective view of the toy car showing my design;

FIG. 2 is a rear perspective view thereof;

FIG. 3 is a front elevation view thereof;

FIG. 4 is a left-side view thereof;

FIG. 5 is a rear elevation view thereof; and

FIG. 6 is a top plan view thereof; and,

FIG. 7 is a bottom view thereof.

Portions of the toy car shown in broken lines form no part of the claimed design.
